UNITED STATES PATENT OFFICE

FREDERICK E. THEILACKER, OF MILWAUKEE, WISCONSIN, ASSIGNOR TO NORMAN P. HARSHBERGER, OF CHICAGO, ILLINOIS

SHINGLE

Application filed August 30, 1926. Serial No. 132,345.

This invention relates to flexible strip shingles and more particularly to composition shingles. However, it is applicable to any type of shingle that is more or less flexible, such as sheet metal shingles. The invention has for one of its objects producing a strip shingle the lap portions of which may be locked down in an improved manner. A further object of the invention is to provide shingles of this nature that can be cut from sheets of shingle material without waste. Another object is to form the shingle so that the above mentioned objects are met, and at the same time the assembled shingles present a very pleasing appearance.

Of the accompanying drawings Fig. 1 is a plan view of a number of the shingles assembled as they are ordinarily laid on a roof; Fig. 2 is plan view of a single shingle; and Figure 3 is a plan view of a somewhat modified type of shingle; and Fig. 4 is an enlarged sectional view along the lines 4—4 of Fig. 3.

Each of the shingles 5 has lap portions 6 projecting from one edge of the shingle. In practice there may be as many of these lap portions as may be desired. I prefer to have only two. Near the outer edge of each of these lap portions is a slit or slot 7 which is adapted to assist in locking down the lap portion when it is laid on a roof. Slits 8 are cut in the main body of the shingles between two lap portions, forming lugs or locks 9 which are adapted to slip into the slots 7 of the overlying shingles and thus to lock down the lap portions 6 of the overlying shingle. Slits 10 are also cut in the body of the shingle, forming lugs 11 therein which are also adapted to slip into the slits 7 of the lap of the overlying shingles.

By a consideration of Fig. 2 it will be seen that each of the laps 6 is locked down by a lug 9 of an underlying shingle, or by two lugs 11 of adjacent underlying shingles. By having strip shingles with two or more lap portions 6, instead of individual shingles with a single lap portion, not only is the cutting and laying of the shingles carried out more expeditiously and cheaper but one of the laps in each shingle, as stated, is locked

by a single lug instead of two lugs, thus improving the appearance and also strengthening the locking; because the single lug 9 is supported by the body portion of the shingle on the two sides, while the lugs 11 are not only weaker, being one-half the width of the tongues 9 if symmetrical, but they are supported on only one side by the body portion. Furthermore, with my shingles fewer nails are required and the shingles are more firmly held in position. They are not only locked together at two points but also two nails will prevent any rotary movement of the entire shingle although the shingles themselves are normally twice the size of individual shingles. Nails 12 are ample ordinarily for supporting the shingles, but if desired nails 13 may be also used. By positioning the nails as indicated the lower portions of the bodies of the shingles are firmly fastened, and, particularly, the portions which support the lugs are held firmly down against the roof.

The particular angle formed between the body portion and the lap portion of the shingle obviously is not material so far as my invention is concerned. In Fig. 3 this angle is materially smaller than in Fig. 2. As a consequence the design of the roof is changed. While the principal figure of the design is a hexagon yet the hexagon is not equilateral as is shown in Fig. 2.

In the modified shingle 14 of the Figs. 3 and 4, the slits 15 are made at oblique angles with the edge of the shingle, instead of at a right angle as is the case with the slits 8 and 10. By making the angles 16 less than right angles, as indicated, the lugs 17 converge towards the outer ends and thus, for a given strength, the lug area is reduced because the greatest stress on the lug is at its point of connection with the body portion, and, for similar shingles otherwise, converging tongues may have the same width at the inner edge. At the same time, by narrowing the outer end of the tongue it is much easier to slip the tongue into the slits 18 when the shingles are being assembled.

Also, these modified shingles 14 are made somewhat unsymmetrical in that the ends 19 extend materially further beyond the lap por-

tion 20 than is the case with the ends 21. This is done in order to provide sufficient length on one of these ends to make a slit 22 and thus form a lug 23 which is spaced from the lap 5 20 the same distance as the lug 17. By this arrangement a lug is not required at the other end of the shingle as the lug 23 takes the place of the lug 11 in one shingle and also the lug 11 in the adjacent end of the adjacent shingle, 10 the tongue 23 slipping into a slot 18 and performing the same function as the lug 17. Also, to improve the appearance of the shingles the slits 15 and 22 are made parallel with the respective adjacent edges of the laps 15 which are locked down by the tongues, thus improving the appearance of the roof as the design of the lug is symmetrical with the design of the laps themselves.

It will be obvious that the modified shingles 14 may be cut from strips of shingle material in a manner similar to the shingles 5, but with the ends 19 and 21 offset as explained; and in order that the lugs 23 may be similar in shape to the tongues 17 a portion 24 is left 25 on the end 21 and taken off from the end 19, of the adjacent shingle. However, in order to form the shingles 14 more symmetrical, the shingle 25 may be used. This shingle is similar to shingles 14, except that a portion 26 30 projects outwardly from one end, which is cut from the other end of an adjacent shingle, so that the edges 27 and 28 are symmetrical with reference to the shanks or laps 29. This arrangement provides for equal laps at the ends 35 of the shingles, instead of a long lap at one end and a short lap at the other end of the same shingle as is the case with shingles 14. This makes a better protection for the roof. For instance, rain could drive under the edge 40 32 to the edge 33 easier than if the edge 33 were opposite the center of the lug 17 of the overlying shingle.

I have herein referred to the laps of the shingles, as the shank portions, 6 or 20, which 45 project from the body portions of the shingles. But it will be seen that the exposed portion of each shingle, which is frequently called the lap, includes a material part of the body portion as well as the shanks.

50 I have found it desirable to make a crimp 52, Fig. 3, in the base of the lugs of these shingles so as to raise the lugs above the bodies of the shingles. This facilitates entering the lugs in the slits, and causes the lugs to lay 55 flat down on the surface of the shingles below the slits.

I claim as my invention:

60 1. A shingle having a body portion, and a plurality of laps projecting from one side of the body portion, each of the laps having a slit adjacent the outer end of the lap, and a lug fixed to the body portion between one end and the adjacent lap, said lug being adapted to pass into a slit in a lap of an overlying 65 shingle, the inner edge of said lug being

spaced from the adjacent lap edge the same distance as the other end of the body is from its adjacent lap edge.

2. A shingle having a body portion, and a plurality of laps projecting from the body 70 portion, each of the laps having a slit adjacent its outer end, and a lug fixed to the body portion between two laps, said lug being adapted to pass into a slit in a lap of an overlying shingle, said shingle having a slit 75 extending into said body portion between one end and the adjacent lap, the latter slit in each shingle being spaced from its adjacent lap the same distance as the other end of the body is from its adjacent lap. 80

3. A shingle having a body portion and two laps projecting from one side of the body, each of the laps having an internal slit adjacent its outer end, and a lug fixed to the body portion between the two laps, said shingle 85 having a second slit extending into the body portion between one lap and the adjacent corner of the body of the shingle, and having the body end adjacent said second slit positioned materially further from the adjacent lap than 90 the distance the opposite body end is from its adjacent lap.

In testimony whereof, I hereunto set my hand.

FREDERICK E. THEILACKER.
